[57] CLAIM

The ornamental design for a combined chip and salsa server, as shown and described.

DESCRIPTION

FIG. 1 is a front elevational view of a combined chip and salsa server showing my new design;

FIG. 2 is the right side elevational view thereof at a reduced scale;

FIG. 3 is the left side elevational view thereof at the same reduced scale as FIG. 2;

FIG. 4 is the top plan view thereof;

FIG. 5 is the bottom plan view thereof at a reduced scale;

FIG. 6 is an exploded top perspective view thereof.
